UNITED STATES PATENT OFFICE.

EMIL TYDEN, OF HASTINGS, MICHIGAN.

SELF-LOCKING SEAL.

SPECIFICATION forming part of Letters Patent No. 710,634, dated October 7, 1902.

Application filed December 23, 1901. Serial No. 86,981. (No model.)

To all whom it may concern:

Be it known that I, EMIL TYDEN, a citizen of the United States, residing at Hastings, in the county of Barry and State of Michigan, 5 have invented certain new and useful Improvements in Self-Locking Seals, of which the following is a specification, reference being had to the accompanying drawings, forming a part thereof.

10 The purpose of this invention is to provide an improved self-locking seal of the general class in which there is a hollow bulb attached to one end of a flexible strap or band, the other end of which is adapted after being inserted through the hasps or staples or an eye 15 in the device to be secured by it to be thrust into the bulb and there engaged automatically with the locking device.

It consists in the improvements in the form 20 of the locking device and means for retaining it in proper position in the bulb and in details of construction fully set out in the claims.

In the drawings, Figure 1 is an axial section of my improved seal. Fig. 2 is a section at the line 2 2 on Fig. 1, showing the locking device in position prior to locking. Fig. 3 is a view similar to Fig. 2, showing the seal with strap inserted, but the locking not effected. Fig. 4 is a similar view showing the seal locked. Fig. 5 is a section of the rings constituting the locking device.

The shell or bulb comprises the dome A and the diaphragm or base A'. B is the securing-strap. It penetrates the bulb protruding therefrom at one end a short distance and having its principal length protruding at the other end. It is made rigid with the shell in any convenient manner, as 35 by being formed with the small shoulders b b, which are stopped at the under side of the aperture a at the crest of the dome, through which one end of said strap emerges, and by similar shoulders b' b', similarly stopped at 40 the margin of the aperture a' at the base or diaphragm of the shell, and by being soldered to the edges of the apertures a and a'. Thus secured there is left in the apertures a and a' at the side of the strap opposite the surface 45 which is soldered to the edges of said apertures sufficient space to admit the other end of the strap, which may be thrust through

the shell at these apertures after being inserted through the device to be secured.

C are two rings within the bulb, which 55 constitute the locking device. In the preferred form of these rings in which they are shown they are made of sheet metal cut first in the annular form and then having struck up from one surface a bead c to stiffen them. 60 They are then rifted at one point by an oblique cut, leaving the crest of the bead at one side of the cut overhanging or lapping the portion divided therefrom at the other side, as clearly seen in Fig. 3. The rings made in 65 this form may be nested—that is, lodged one upon the other, with the bead of one seating in the opposite recess or cavity under the bead of the other. In construction the two or more of these rings employed are assembled— 70 that is, nested—with their said oblique slots coinciding and spread at said slots, so that they may be passed over the edge of the strap B, as seen in Fig. 2. The strap B has an aperture B' in the portion which is secured in 75 the shell, and the rings c c, &c., are lodged upon the strap in the manner described, with their laterally-spread ends clasping the latter between them at a point a little above—that is, toward the crest of the bulb from the 80 position of said aperture. Any convenient means may be employed to oppose the movement of the rings down to the aperture, but not to prevent such movement absolutely when sufficient pressure is applied. I have 85 shown as the means for effecting this result a slight deflection of the strap just above the aperture in the path which the clasping ends of the rings would have to follow to reach the aperture, such deflection B² making a little 90 extra pressure upon the ring necessary to force it over the obstruction of the deflection. The natural resiliency of the rings from the 95 stiffness imparted by the bead causes it to stand normally in the position shown in Fig. 2 when spread to clasp the strap, and in this position it will be noticed that an acute angle is formed between either face of the strap and the proximate face of the ring. At one side it is the crest or edge of the bead which 100 makes this angle with the proximate surface of the strap, while at the other side it is the oblique face of the cut made across the bead which makes like angle with the surface of

the strap at that side. It is immaterial which of these surfaces of the strap is the one lodged against and soldered to the margin of the apertures a and a' of the shell; but I have shown 5 the strap secured at the first-mentioned surface—that is, the one which makes the acute angle with the crest—so that the other acute angle formed between the opposite surfaces of the strap and the oblique cut of the bead 10 is presented toward the orifice remaining for the insertion of the free end of the strap. The strap has near its free end a slit B^3 , large enough to permit the rings to freely pass through the same. The end of the strap is 15 preferably cut away to give it a slight taper, such taper ending in a slight shoulder C^3 . This shoulder is at such position that when the end of the strap is inserted down through the aperture a alongside the fixed end of the 20 strap, thence down into the acute angle between the oblique cut of the ring and the proximate surface of said fixed end, and thence on between the said obliquely-cut end of the ring and the strap the shoulder en- 25 counters the opposite side of the ring at the time the slot reaches said obliquely-cut end and becomes lodged therein. The further intruding movement of the strap causes the shoulder to carry the ring with it, sliding it 30 down on the fixed end of the strap over the obstruction of the deflection B^2 until the ends of the rings come opposite the aperture B' , when the rings will recoil into closed position, the ends taking immediately through 35 the aperture, and thus by engagement through both the aperture B' and the aperture B^3 , securing the inserted end of the strap in the bulb. The recoil tends to cause the rings to fly around in the apertures, so that the slits 40 no longer coincide therewith, and the same cause—to wit, the recoil—tends to separate the two or more nested rings which will not recoil equally, and this makes their slits take different positions instead of being, as they 45 are up to that point, coincident. By the time this engagement has been effected the end of the strap is protruded entirely through the bulb and appears at the base, closing the crevice remaining of the aperture a' , and thus 50 tends to prevent access into the shell for the purpose of tampering with the lock.

I do not limit myself to the particular form of rings shown made of sheet metal with a bead, as described, though it has advantages, 55 such as the nesting of one within another, tending to keep the beads concentric after they are locked, and making it somewhat difficult to discover the location of the respective slots, and also having the effect to 60 make them assume without special contrivance the position relative to the secured end of the strap which is shown in Fig. 2—that is, presenting an acute-angled entrance for the inserted end of the strap between the fixed 65 end and the ring. Substitutes for these advantages may in part be obtained with other forms of ring in ways which will be obvious

to the mechanic. Neither do I limit myself to the described method for holding the rings in position in which they are assembled and 70 prevent them from being crowded onward to the position at which their ends might engage the aperture B' before the end of the strap becomes practically entered through the slit in the rings, so as to have the ends of the latter engage its slot B^3 . Other means beside the deflection of this strap at B^2 will occur to the mechanic, and substitution of other means for this purpose would not be a departure from my invention. 75 80

It will be clear upon consideration that the portion of the strap which is fixed within the shell has a function of its own distinct from that of the securing-strap proper, and I do not limit myself to making this strap or bar 85 on which the lapped ends of the ring are clasped within the shell as a part of the securing-strap.

I claim—

1. A self-locking seal comprising a shell 90 apertured to admit a securing-strap; a ring lodged within the shell having its ends lapped by each other and adapted to be spread laterally to admit the strap between them; means for holding the ring in the shell with its lap exposed in the path of entry of the strap, and such strap having an aperture through which the lapped ends of the ring may pass when the strap is entered between them; and means by which the full entry of the strap releases 100 the ring from the holding device. 95

2. A self-locking seal comprising a shell apertured to admit a securing-strap, such strap having one end permanently secured to the shell and the other end adapted to be inserted into the same at the said aperture; a ring lodged within the shell having its ends lapped by each other and adapted to be spread to admit the strap between them; means for holding the ring in the shell with its lap exposed in the path of entry of the strap, the strap having an aperture through which the lapped ends of the ring may pass when the strap is entered between them; and means by which the full entry of the strap releases 115 the ring from the holding device. 105 110

3. A self-locking seal comprising a shell apertured to admit a securing-strap, and such strap having one end extended within and permanently secured to the shell, and the other end adapted to be inserted through the apertures alongside the secured end; a ring within the shell having its ends lapped by each other and clasping the strap fixed within the shell between them, said portion of the 125 strap having within the shell an aperture through which the ends of the ring may pass; means for resisting the movement toward such aperture of the ring clasped on the strap, the free end of the strap being adapted when 130 inserted in the shell to enter the lap of the ring alongside the fixed end, and having an aperture adapted to lap the aperture of the fixed end and to receive the lapped ends of 135

- the ring, and provided with means for disengaging the ring after said aperture reaches said ends and for carrying the ring to the aperture in the fixed end.
- 5 4. A self-locking seal comprising a shell and a securing-strap having one end fixed in the shell and the other end adapted to be inserted into the shell alongside the fixed end, the shell having apertures to permit such insertion; a plurality of rings lodged in the shell having their ends lapped by each other and clasping between them the fixed end portion of the strap within the shell, said fixed end portion having an aperture beyond the point 10 at which it is clasped by the rings, adapted to receive the ends of the rings, the free end of the strap having an aperture also adapted to receive said ends of the rings, and being adapted to enter the lap of the latter when 15 inserted alongside the fixed end, and provided with means for moving the rings after its aperture reaches their ends, carrying said ends to the aperture in the fixed portion of the strap.
- 20 5. A self-locking seal comprising a shell apertured to admit a securing-strap; a plurality of rings having their ends respectively lapped by each other; means for holding them in the shell with their laps all exposed in the 25 path of entry of the strap; the securing-strap adapted when entered to pass into the laps of the rings and having an aperture to receive their ends, and provided with means for releasing the rings from the holding devices 30 after the aperture reaches said lapped ends.
- 35 6. In a self-locking seal having as the locking device a ring which is lodged unattached within the shell when the locking is effected, such locking-ring being made of sheet metal 40 annularly beaded and having its ends lapped by being cut obliquely through the bead.
- 45 7. In a self-locking seal having for the locking device a plurality of rings which are unattached when the locking is effected, such locking-rings being made of sheet metal annularly beaded and adapted to be nested bead within bead, the ends of such rings being rendered lapped by being cut obliquely across the bead.
- 50 8. A self-locking seal comprising a shell apertured to admit a securing-strap; a strap or bar fixed within the shell; a securing-strap adapted to be inserted through the aperture
- into the shell; a ring having its ends lapped and clasping the fixed strap or bar between them, and having its lap thereby held exposed in the path of entry of the securing-strap, the latter having in its inserted end an aperture to receive the lapped ends of the ring, and means by which it is adapted to dislodge 60 the ring from clasping position on the fixed strap by its movement after said aperture reaches said ends.
9. A self-locking seal comprising a shell apertured to admit a securing-strap; a strap 65 or bar fixed within the shell; a securing-strap adapted to be inserted through the aperture into the shell; a locking-ring having its ends lapped and clasping the fixed strap or bar between them, said strap or bar having one face 70 in the path of entry of the securing-strap, whereby the ring clasped thereon is held with its lap exposed in said path of entry, the securing-strap having in its end an aperture adapted to receive the lapped ends of the 75 ring; and means by which it dislodges the ring from clasping position on the fixed strap or bar by its movement after such aperture reaches the lapped ends.
10. A self-locking seal comprising an aper- 80 tured shell; a securing-strap adapted to be inserted through the aperture; a strap or bar fixed within the shell having one face in the path of entry of the securing-strap; a lock- 85 ing-ring having its ends lapped and clasping the fixed strap or bar between them, whereby the ring is held with its lap exposed within the path of entry of the securing-strap, the latter having an aperture adapted to receive the lapped ends of the ring, the fixed strap 90 or bar having an aperture adapted to receive said ends located beyond the position at which said ends are clasped on said bar; and means by which the movement of the securing-strap after its aperture reaches the lapped ends, 95 carries said ends to the aperture in the fixed strap or bar.
- In testimony whereof I have hereunto set my hand, in the presence of two witnesses, at Chicago, Illinois, this 14th day of December, 100 A. D. 1901.
